COVERED TOP CONSTRUCTION FOR
DESKS AND THE LIKE

Niels Yde Andersen, Snyder, N. Y., assignor to
Remington Rand Inc., Buffalo, N. Y., a corporation of Delaware

Application April 30, 1947, Serial No. 744,903

6 Claims. (Cl. 311—106)

1

This invention relates to a desk or table top construction, and it has particular reference to the provision, in a desk, table, or like article of manufacture, of improved means for finishing the edges of the top and securing a plastic covering material thereon.

The tops of many desks and tables are provided with a covering of linoleum or other plastic sheet material which extends over the entire surface, and is bound in some manner along the side edges to secure the covering in place. While a number of proposals have been made for ways to bind the covering, many of them have been found objectionable, either from the loosening of the cover, or from rough edges or large cracks which admit dirt.

The present invention contemplates improvements in constructions of this class, and proposes a top construction having a cooperating edge binding and corner construction which will firmly secure the covering, conceal all rough edges, reinforce the construction as a whole, and give a desk or table top an attractive appearance. The invention also provides an edge construction for slidably and detachably receiving and retaining an edge binding strip for the linoleum or similar top covering, with corner members detachably mounted on the corners of the top and retaining the edge binding strips in engaged position.

In the drawings:

Fig. 1 is a fragmentary perspective of a corner of the top, with portions broken away to show the details of construction, and with certain portions removed for clarity of illustration;

Fig. 2 is a similar fragmentary perspective showing particularly the edge binding strips in position;

Fig. 3 is a perspective of a corner block adapted to be located in the corner of the top looking at the inner portion thereof;

Fig. 4 is a horizontal cross-section of the corner after assembly, taken about midway along the edge, and substantially as indicated by the line 4—4 in Fig. 5;

Fig. 5 is a vertical cross-section of the corner after assembly, taken adjacent the point of abutment of one edge with one vertical face of the curved corner piece and parallel to that face;

Fig. 6 is a horizontal cross-section through the corner, taken substantially on line 6—6 of Fig. 5; and

Fig. 7 is a vertical cross-section taken diagonally through the corner, and substantially along line 7—7 of Fig. 4.

2

The desk or table top construction as illustrated in these views comprises a sheet metal deck 11 which is pressed or otherwise formed along its margins to provide a generously curved section 12, merging into a reentrant flange 13 which is turned down to provide a terminal flange 14. The material of deck 11 is stamped at suitable spaced intervals along reentrant flange 13 to provide depending lugs 15 whose outer faces are substantially contiguous with and tangent to curved edge 12. These lugs cooperate with other elements of the construction as hereinafter described.

The deck 11 is reinforced and curved sections 12 are prepared for the reception of binding strips by means of step-shaped members 16 and 17 extending along the margins on the under side of the deck. Except at the corners, each member 16 or 17 comprises a flange 18 parallel to and abutting deck 11, and welded thereto to integrate the members. The flange 18 merges into successive web portions 19 and 21, at right angles to each other, while the web 21 merges into a depending flange 22 abutting the inner side of terminal flange 14, and flange 22 is bent to form a lateral flange 26 and a continuous upstanding lip 27. Contacting flanges 14 and 22 may also be welded at intervals, and flanges 18 are mitred and web 19 of member 17 is cut away to form joint 23, providing a hollow box-like edge, defined by curved edge section 12 and adjacent portions of the deck, and the two right-angled webs 19 and 21.

A right angled portion is cut out of deck 11 by cuts 24 and 25 in planes perpendicular to the top and each other. Flanges 22 and 26, and lip 27 are also cut away from webs 21, leaving overlapping extensions 216 and 217. To provide this overlapping, web 19 of member 17 is made wider than the corresponding web 19 of member 16, and the latter web 19 has a step cut out at its end to allow for the curvature of curved section 12. These cut away portions and the square corner formed by extensions 216 and 217 receive and position corner piece 41 which has an outer curved surface, as shown in Fig. 3. When corner piece 41 is inserted it joins the marginal portions of curved sections 12 and the plane area of deck 11 to form a substantially smooth and continuous surface.

When the foregoing parts are framed and assembled, the deck 11 is provided with a cover 31 of linoleum or other suitable surfacing and finishing material, which may be cemented to the plane area of the deck in the usual manner, and which has a marginal portion 32 overlapping

curved section 12 and extending below reentrant flange 13. The free edge of the cover thus acts as a curtain partially covering the channel formed between flanges 13 and 26. This edge is secured by a binding strip or molding 33, as best shown in Figs. 2 and 5.

The molding 33, which may be formed of plastic material, comprises in section a head portion having an outer curved surface 34 adapted to overlie portions of lip 27 and the edge of cover 31, a plane back 35 adapted to abut depending flange 14 of deck 11, and upper and lower longitudinal grooves 36 and 37. The groove 36 is sufficiently wide and deep to receive with a tight fit the free edge of cover 31 and lugs 15 of deck 11, thus locking the molding from displacement outwardly, and pinching the edge of the cover material tightly in place. The lower groove 37 is smaller, being just large enough to engage lip 27 which is aligned with the lower edge of curved section 12 and thereby further secure the molding in place. The back of the molding is moreover advantageously provided with a slot 38, to impart some flexibility. In assembly, suitable lengths of molding are pushed endwise into the channels formed by the flanges 13, 14, and 28, this method of assembly being permitted by the cut-away corners of the top which provide the necessary clearance. Continuous lengths of molding may therefore be employed to engage 30 the cover 31 throughout its length, and to provide a smooth and attractive appearance. As shown in Fig. 2, the ends of strips 33 project slightly into the space defined by the cut-away corners.

The previously referred to corner piece, shown in Fig. 3 and hereinafter designated generally by the reference numeral 41, may also be formed as a molded plastic article, having a smooth or ornamented and continuous outer surface adapting itself to the curvature of edge section 12. The inner surface of this article has an irregular surface, shown in Fig. 3, and also in section in the remaining views. As best illustrated in Figs. 3 and 4, the inner vertical marginal portions of the corner block are beveled, as indicated by reference numeral 42, to engage the edges of the cover 31 which are also scarfed to provide a blind and secure joint. The upper inner surface is provided with a centrally located projection 43 having a beveled upper edge 44, so positioned as to pass under the surface of deck 11 and act as a centering and locating boss. At the mid-section, the block is shaped to have a plane surface 46 positioned diagonally with respect to the corner, and this surface is drilled and tapped to provide a bolt hole 47. The under surface of the portion 46 is also plane, and is so located to rest upon the web section 216, which thus provides a support for the block.

The lower portion of the block is formed to provide right-angled faces 48 and 49, which thereby exposes a horizontal surface 51 for engaging the web extension 216. These faces extend to the bottom surface 52. Adjacent the junction of the side edges 42 and the bottom 52, the side edges are cut back to provide sockets 53 and 54 which accommodate the projecting ends of molding strips 33, thus housing these ends and forming a concealed joint on each face of the corner. Notches 55 enable the block to abut the ends of flanges 22 and 26, so that, upon assembly, the entire corner region is framed in such manner as to minimize the possibility of dirt accumulations, and the existence of pro-

truding edges which might snag the clothing or fingers.

Each corner block 41 is held in position by a bolt 56 which passes through apertures 57 and 58 formed in flanges 19 of members 16 and 17, and which is secured by an angle washer 59 and a nut 61. The bolt 56 may be assembled with the block 41 prior to positioning the block, the nut 61 being taken up subsequently, thereby to safeguard against possible injury to the corner block if the assembly were made the other way.

It will be seen that both the edge molding 33 and the corner block 41 may be easily positioned and that they cooperate at the corners to provide a finishing and binding means securing the cover material and effectively protecting the joints. The construction of the deck and its connected step members 16 and 17 moreover provide a strong and resistant edge binding or border construction, well adapted to resist the stresses imposed on furniture of this nature. Inasmuch as the invention is concerned with the features previously described, it is deemed unnecessary to illustrate or describe the complete piece of furniture, as it will be apparent that the tops can be applied to tables, desks, cabinets, and like articles, with equal facility.

The invention claimed is:

1. In a furniture top, a deck member having a flat top and a curved depending margin, said margin merging into a reentrant flange and a perpendicularly depending flange, reinforcing members secured to the under side of the deck parallel to the edges thereof and having downwardly and outwardly extending webs, said outwardly extending web abutting said depending flange, a second depending flange formed contiguous with the depending flange of the deck, said second depending flange merging into a perpendicular lateral flange underlying said reentrant flange, said lateral flange being turned up to provide a lip underlying the curved margin, and lugs integrally struck out from the reentrant flange in parallel alignment with the lip, thereby to form a reinforced edge including a channel for the reception of a binding member, said binding member having oppositely disposed integrally formed grooves to receive said lugs and said lip, respectively therein.

2. In a furniture top, a deck member formed with a downwardly curved marginal portion reinforcing members carried by said deck member and dependent therefrom, said members being turned outwardly and upwardly to form a channel shaped recess below the curved portion, said marginal portion and recess being cut away at the corners of the deck, a cover over the deck and extending downwardly to overlap said recess, securing strips longitudinally slidable in said recess, said securing strips being arranged with longitudinal grooves on opposite sides thereof to engage said cover and the upturned portions of said channel forming members, respectively, to retain the cover, and detachable corner blocks positioned in the cut-away corner portions of the deck to engage portions of the cover above the recess and to conceal the edges thereof and the ends of the securing strips.

3. In a furniture top, a deck member formed with a plane top area and a depending curved margin, the corners of said margin being cut away at substantially right angles for a depth sufficient to locate the apical intersection of the cuts in said plane area, reinforcing members secured to the underside of the plane area of the

deck and extending substantially the length of each side thereof, said members being formed with depending and outwardly extending webs to form a hollow box-like member beneath the deck, said members being mutually cut and overlapped to form a square corner positioned in the cut-out area of the margin, a corner block positioned in said cut-out area, said block having a curved outer surface merging with the curved margin along adjacent sides of the deck, said block being formed on its inner surface with a recess receiving said overlapped reinforcing members and with a ledge resting on the upper horizontal surface thereof.

4. In a furniture top, a deck formed with a plane upper surface and depending curved margins, said marginal portions adjacent each corner of the deck being cut away along lines disposed at right angles to each other, reinforcing and supporting members secured to the underside of the deck and extending at right angles into the area defined by said lines and between the plane upper surface and the curved margins, a cover disposed on the deck and extending downwardly over the margins, means intermediate the corners for securing the cover along the edges thereof, said cover, along said lines, being scarfed, and a corner block detachably positioned in each corner, said block having beveled vertical edges engaging the scarfed edges of the cover, a ledge adapted to rest upon said reinforcing and supporting members, and means extending from the inner face of said block and under the deck for holding said block in position.

5. In a furniture top, a deck having a plane upper surface and curved depending marginal portions, said marginal portions, adjacent the corners, being cut away to provide regions delineated by substantially right angled edges having the same radii as the said marginal portions, reinforcing members secured to the under side of the deck and extending downwardly and outwardly to the lower edges of the curved marginal portions, flanges extending inwardly from and below said curved marginal portions and being turned outwardly and upwardly to form a channel shaped recess underlying said curved marginal portions, said flanges also being cut away at the corners, a cover positioned over the deck and having edges overhanging said recess, molding strips positioned in said recess to engage and bind the edges of the cover, said molding strips projecting beyond the ends of the flanges to project into said corner regions, a block detachably mounted at each corner to fill each of said regions, said block having a curved outer

surface adapted in each horizontal plane to continue the curvature of adjacent marginal portions around said corner, beveled edges adapted to overlap the edges of the margins to engage the cover therebeneath, recessed portions overlapping and concealing the projecting ends of the molding strips, and projecting portions on the inner face of the block engaging the under side of the deck and said reinforcing members to locate and support said block.

5 5. In a furniture top, a deck having a plane upper area merging along each side into a downwardly curved margin, channel sectioned flange members secured to said deck and underlying said curved margin to provide a recess along each side of the top for a molding strip, reinforcing members secured to the under side of the deck, each said reinforcing member having a depending vertical flange and a laterally extending flange engaging said channel sectioned flange members, said laterally extending flanges forming a square corner between adjacent sides of the deck, said curved margin and flange members being cut away at each corner, a cover for the deck having edges overhanging said recess, molding strips in the recesses to engage and secure the cover, said strips projecting beyond the flanges into the cut away corner region, and a corner block secured to each corner, said block having a curved outer surface continuing the curvature of said margins between adjacent sides of the deck, beveled edges on said block adapted to overlap and secure the edges of the cover at said corners, recessed portions overlapping and concealing the projecting ends of the molding strips, and a threaded socket on the inner face of the block for engaging a bolt, the opposite end of the bolt being engaged at a vertical depending flange of a reinforcing member.
